UNITED STATES PATENT OFFICE.

PAUL MOUTON, OF PARIS, FRANCE, ASSIGNOR TO CHENEY BROTHERS, OF SOUTH MANCHESTER, CONNECTICUT, A CORPORATION OF CONNECTICUT.

DESIGN FOR TEXTILE FABRIC.

40,902.

Specification for Design. Patented Sept. 20, 1910.

Application filed May 21, 1910. Serial No. 562,784. Term of patent 3½ years.

To all whom it may concern:

Be it known that I, PAUL MOUTON, a citizen of the French Republic, residing at Paris, France, have invented a new, original, and ornamental Design for Textile Fabrics, of which the following is a specification, reference being had to the accompanying drawing, forming part thereof.

The drawing illustrates a section or portion of a fabric embodying my new design.

I claim:

The ornamental design for a textile fabric, as shown.

PAUL MOUTON.
